SHEET SORTING MECHANISM

Curt Uschmann and Elmer H. Jacobson, Lebanon, Oreg., assignors to Cascades Plywood Corporation, Portland, Oreg., a corporation of Delaware

Application April 16, 1945, Serial No. 588,626

7 Claims. (Cl. 214—11)

1

Veneer, on being peeled from the log, is carried along a green chain past a clipper, where it is cut into widths which are approximately four feet; or if it contains defects these are cut out, resulting in narrower pieces. As the log is peeled, the veneer is composed of sap wood and heart wood, and it is desirable to segregate these types of wood, as well as wide heart pieces and narrow heart pieces, and in addition to segregate all such usable sheets from the reject sheets which are clipped out. This sorting as to grade, kind, and width requires, under present practices, the services of a number of individuals stationed along the run of the green chain, whose duty it is to select and segregate the different kinds and widths of veneer, and to stack it for further treatment. All that is not thus selected and segregated by the time the veneer reaches the end of the green chain is delivered into hoppers as reject veneer, and eventually is burned or otherwise disposed of. Since the veneer is traveling at fairly high speed, it is not possible to correctly evaluate all pieces as they pass along, and moreover, as the operators become tired, particularly toward the end of the day, it is inevitable that an appreciable quantity of usable veneer is not sorted out but is left to run on to the reject hopper. Appreciable loss thus occurs in a material which presently is in very scarce supply, and under any circumstances there is an unwarranted waste of an important natural resource.

It is a general object of this invention to provide mechanism for handling and sorting such veneer which will simplify the proper sorting, and which will prevent such loss.

More particularly, it is an object to prevent such loss by insuring that all veneer will be directed primarily to one or the other of several collecting places for usable veneer, so that a positive choice is necessary before any sheet can be directed to the reject depository. Thus positive rather than passive rejection is required.

Also, and more particularly, it is an object to simplify the sorting by effecting the sorting mechanically, under control of an operator, and by thus simplifying the sorting to make it possible to effect the sorting with a minimum use of manpower and the minimum number of operators. In so doing a further object is attained, namely uniformity of grading, for all grading along a given green chain may be done by a single operator.

In sorting the greater quantity of veneer will be rated as sap veneer, and the wide heart and

2

narrow heart selections will not accumulate at the same rate as the sap veneer accumulates, nor will there be the same quantity or the same rate of accumulation of wide heart veneer as of narrow heart veneer. It is a further object of the invention to enable the full loading of a vehicle with one selection of veneer, that is, one grade or one kind, regardless of the rate of accumulation of other grades or kinds, and the removal of such vehicle when filled, and the delivery of the same kind or grade to another vehicle, without any interruption whatsoever in the operation of the sorting mechanism.

This invention will be illustrated in apparatus which is suitable to the end intended, and to carry out the method which constitutes part of the invention, and in the disclosure of this apparatus various other details and objectives will become apparent.

20 In the accompanying drawings the invention has been shown in a form which is at present the preferred form, but it will be understood that various changes and modifications may be made within the scope of the invention, as hereinafter disclosed and claimed, without departing from the spirit and intent of the invention.

Figure 1 is a general side elevation, as indicated by the line 1—1 of Figure 2, and Figure 2 is a general plan view of the machine.

30 Figure 3 is a side elevation and Figure 4 a plan view, the general extent of these views being indicated by the line 3—3 alongside Figure 1.

Figure 5 is an elevation and Figure 6 a plan view, with parts broken away, illustrating a continuation of Figures 3 and 4, respectively, the extent of these views being indicated by the line 5—5 alongside Figure 1.

40 Referring first to Figures 1 and 2, the supply conveyor 1 may be a continuation of the chain which bears the veneer to and past the clipper, but preferably it is an extension thereof operating at a somewhat higher rate of speed. It bears all veneer sheets from a supply point or source, as designated on Figure 1, to a reject depository, not shown, but the approximate location of which is there indicated, provided of course that the sheets are not intercepted between these points, as normally they will be. In addition to the reject depository there are several receiving platforms, or chutes, which may be in all essential respects alike, and which have therefore been represented by the numeral 3. To distinguish them the several receiving platforms are designated WH for wide heart, NH for narrow heart, and S for sap. Preferably the several receiving

platforms 3 are in the form of off-bearing conveyors, such as live rolls, arranged to convey sheets which are deposited upon them off to one side or the other of the supply conveyor 1, and they operate at a speed materially greater than 5 the speed of advance of the supply conveyor 1. They are conveniently located above the latter.

Associated with the generally aligned series of receiving platforms 3 is a series of conveyor means, which are substantially alike and which are designated generally by the numeral 4. For the purpose of distinguishing the several sections of the conveyor 4, or the several elements thereof, these too may be designated by the letters WH, NH, and T, the latter indicating a transfer section which precedes the first receiving platform. For reasons which will shortly appear, it is not necessary that there be a conveyor element disposed above the S section 5, similarly as the other sections are disposed above 10 their respective platforms at the stations NH and WH. The conveyor means 4 conveniently lie generally above the receiving platforms 3.

There is also a switch element 2 which is associated with the supply conveyor 1, and which, being in advance of all of the conveyor sections 4, is normally disposed inclined upwardly from the supply conveyor 1 in the sense of the advance, to intercept all sheets oncoming along the supply conveyor, and to deliver them as they advance to the conveyor means 4. The switch element 2 is preferably in the form of a conveyor. It may be moved into an inoperative or open position so that, functioning as a switch, it will permit a sheet, advancing along the supply chain, to pass undeflected beneath the first conveyor means 4, and thus to be carried along the supply chain to the reject depository. The normal position of the switch element 2, however, is inclined upwardly, as shown in Figure 1, and it so remains except as and while it is positively shifted into nondeflecting position.

It is desirable that the conveyor element 4 operate at a speed which is intermediate the higher speed of the off-bearing conveyors 3 and the relatively lower speed of the supply chain 1. In similar fashion the switch element 2 may operate as a conveyor at a speed which is intermediate that of the elements 4 and the conveyor 1. For example, if the clipper chain operates at a speed of 135 feet per minute, the supply chain 1 may operate at a rate of 160 feet per minute, the switch conveyor 2 at a speed of 200 feet per minute, the conveyor means 4 at a speed of 250 feet per minute, and the off-bearing conveyors 3 at a speed of 350 feet per minute. The result is, there is a progressive widening of the gaps between clipped sheets as they follow one another, and by the time a sheet reaches the off-bearing conveyor 3, it is sufficiently in advance of the following sheet that, even though the following sheet is delivered to the same off-bearing conveyor, the preceding sheet will have been moved endwise out of the way before the following sheet is delivered thereto. It has been attempted to show the relative speeds of the several conveyors graphically by the relative sizes of the arrows which indicate their sense of feed. It will be noted, in Figure 2, that dash line arrows have been shown leading to the left of the sense of feed through the machine at the WH, NH, and S stations, in addition to the full line arrows leading off to the right from the sense of the advance. The purpose of this is to indicate that the sense of rotation of the rolls constituting the

off-bearing conveyors can be reversed, so that when a vehicle receiving any given grade at one side of a given station is loaded, the rolls, at this station only, can be reversed to feed to a vehicle already located at the opposite side of the machine, to the end that there be no interruption in the operation of the device.

In addition to the switch means at 2, each of the conveyor elements 4 is or has associated with it a similar switch means, except that the transfer section T need not be so arranged. Thus, as is indicated in dash lines, the WH section 4 may be either in its normal aligned position, with respect to the T section 4, thereby to pass all sheets over and through the section WH without delivery to the platform 3, or this WH section 4 may be raised as indicated in dash lines, to deflect a sheet onto the WH platform 3. Similarly, the normal position of the NH section 4 is down in alignment with the WH section 4, so that all sheets will normally pass through and beyond the NH station and be delivered to the S station. However, if it is desired to divert a sheet to the NH platform 3, the NH conveyor 4 may be raised as a switch, and the sheet is then deflected and delivered, as it leaves the end of the WH conveyor 4, upon the NH platform 3.

The normal operation, then, is to deliver the sheets along the supply chain 1, where they first 20 meet the upwardly inclined switch element 2, passing thence to the T section 4, and finally, if not selected and switched off prior to reaching the S section 3, they are delivered to the latter. Any reject piece is initially and finally segregated 25 by dropping the rear end of the switch means 2 to or below the level of the upper run of the supply conveyor 1, and such reject piece passes beneath the forward end of the T section 4 and on to the reject depository. The operator then permits the switch means 2 to rise into alignment 30 with the T section 4, and by proper manipulation of the controls for the WH and NH sections 4, he accomplishes delivery of each sheet (which becomes well separated from the following sheet due 35 to the different successive rates of advance) into any one of these sections, including the S section, where it is immediately carried out to one side or the other, assuming the receiving platforms to be formed by live rolls.

Given the general arrangement and the method of operation, as above, the structural details may vary considerably, and in themselves are of lesser importance. They are best understood by reference to Figures 3 to 6, inclusive. The supply conveyor 1 is in the form of spaced belts extending around pulleys 10 upon a shaft 11, carried in a suitable frame. A belt tightener is indicated at 12 (see Figure 3). Drive means are not indicated for this conveyor, but may be any which common practice indicates as suitable. The switch means, generally designated by the numeral 2, comprises a series of belts mounted upon pulleys 20 and 21, the latter of which are carried at the swinging upper end of arms 22. These arms 22 may be raised or lowered by means of an air cylinder 24 or similar power means operating through an arm or arms 25 upon the rock-shaft 23, and connected in turn to arms 22 40 by links 25. The air cylinder 24 is so arranged that the switch element 2 is at all times in up-raised position, except when the air cylinder is energized to depress it flush with or below the level of the supply conveyor 1, as shown in dash lines in Figure 3. Such a control may be ini-

tiated by the push button 29, see Figure 4, located at a convenient control station.

The transfer conveyor 4 may consist of a plurality of belts supported between rollers 40 and 41 journaled in opposite sides of a frame 42 which is fixed in the main frame F. This transfer conveyor 4, if used, may be inclined slightly upwardly from a point spaced above the upper run of the supply conveyor 1, as a continuation of the switch section 2, to convey material from the switch section 2 upward to a level to deliver it to the upper run of the WH section 4. Except for the greater length and mass entailed, the transfer conveyor might be an integral part of the switch means 2, or omitted altogether. The transfer section 4 is driven through the medium of a drive chain 43 from a motor 44.

The WH and NH sections 4 are identical in construction to the T section 4 already described, except that each is pivoted about its rear pivot 41 (see Figures 5 and 6) so that its forward edge may rise from a normal position in alignment with the conveyor section just ahead of it, to a position above that level such that oncoming sheets will be deflected below it and on the off-bearing conveyor 3. To this end an air cylinder 45 mounted upon the main frame F is connected by bell crank means 46 and link 47 to the swinging end of the frame 42 to raise it as and when necessary. The control for the several cylinders 45 may be by means of the buttons wh and nh (see Figure 4). The section drops back to normal down position when the control button is released. The individual drive for each of these swinging sections 4 is delivered to its pivoted end.

The live rolls 3 of each individual off-bearing conveyor are connected by chains 39 to drive all in one sense or in the other, and each section is independently driven by its motor 31 and chain 32. Reversal of the direction of rotation of the motor 31 is accomplished by means of control buttons (not shown) corresponding to the buttons nh and wh, except that there will be further buttons to control the direction of rotation of the rolls at the station S.

It will be evident also that in some instances the switch elements and the controls therefor may be actuated, not through the interposition of human judgment, but automatically under the influence of a characteristic of the sheet being handled, as for instance its width, or its length, or its weight, or some other characteristic, hence when such switch elements are said to be movable "under control" it is only implied that the control is manual or automatic, and may be either.

The off-bearing conveyors 3 are generally parallel and transverse to the direction of advance of the supply conveyor 1, which advances along a straight line. If, however, the supply conveyor 1 should be directed along a curved path, for example, the off-bearing conveyors might still be generally "parallel," not in the strict geometrical sense, but rather in the sense that each leads away from the supply conveyor. If the latter is arcuate the off-bearing conveyors might radiate from the latter, and still be considered parallel to one another within the meaning given to such term as used herein. Instead of conveying means, there may be only platforms, or chutes, to receive the sheets.

Useful as is the sorting assembly herein described in handling and sorting veneer, it will be evident that the same may be used for the sorting and handling of various types of mate-

rials, and hence it is not desired by the use of the term "sheets" to limit the assembly to the handling of veneer sheets only, or sheets of any particular size or other characteristic. The sheets may be long and narrow, or long and wide, in fact, square, or they may be of irregular size. They may be a piece of veneer, a piece of sheet metal, a panel of plywood, or indeed almost any material; a plank or even assemblies may be thus handled and sorted. While the machine is primarily intended and best adapted to handle thin veneer sheets, it may handle all such devices as indicated above, by proper design, and indeed may handle materials having appreciable or even irregular depth vertically.

Primarily, and as now will be clear, the "sheets," by which term is intended to include the materials indicated above, are primarily and normally deflected off the supply conveyor and are conveyed to a receiving platform or conveyor where, if not sorted into a different grade, all are delivered into a usable grade. Conscious selection and positive action is necessary to send any piece to the reject depository. Similarly, in the preferred arrangement, conscious selection and positive action is required to deliver any piece to a receiving platform other than the final one.

We claim as our invention:

1. A sheet-sorting assembly comprising a driven supply conveyor extending uninterruptedly from a supply source to a reject depository; a switch element biased into and for return to a normal position wherein it is upwardly inclined from said supply conveyor, to intercept and divert all sheets as they advance; means to depress said switch element, under control, to permit reject sheets to continue along said supply conveyor to the reject depository; a series of aligned conveyor means normally disposed to receive in succession sheets from said switch element, for conveyance past the end of the last such means to a final receiving station; and means operable under control to elevate the advanced end of any selected conveyor means out of alignment with the preceding such means, to divert downwardly an oncoming sheet to a receiving station beneath the thus-raised conveyor means.

2. A sheet-sorting assembly comprising a driven supply conveyor extending uninterruptedly from a supply source to a reject depository; a switch element biased into and for return to a normal position wherein it is upwardly inclined from said supply conveyor, to intercept and divert all sheets as they advance; means to depress said switch element, under control, to permit reject sheets to continue along said supply conveyor to the reject depository; a transfer conveyor aligned with and receiving sheets from said switch element; a series of conveyor means normally aligned each with all other such means, and with the off-feeding end of said transfer conveyor, to receive in succession sheets from said transfer conveyor, for conveyance past the end of the last such means to a final receiving station; and means operable under control to elevate the advanced end of any selected conveyor means out of alignment with the preceding such means, to divert downwardly an oncoming sheet from the transfer conveyor to a first receiving station beneath the first conveyor means, or from any preceding conveyor means to an intermediate receiving station beneath the thus-raised conveyor means.

3. A sheet-sorting assembly comprising a driven

supply conveyor extending uninterruptedly from a supply source to a reject depository; a switch conveyor driven at a more rapid rate than said supply conveyor, biased into and for return to a normal position wherein it is upwardly inclined from said supply conveyor, to intercept and divert all sheets as they advance; means to depress said switch conveyor, under control, to permit reject sheets to continue along said supply conveyor to the reject depository; a series of conveyor means driven at a more rapid rate than said switch conveyor, and normally aligned to receive in succession sheets from said switch conveyor, for conveyance past the end of the last such means to a final receiving station; and means operable under control to elevate the advanced end of any selected conveyor means out of alignment with the preceding such means, to divert downwardly an oncoming sheet to a receiving station beneath the thus-raised conveyor means.

4. A sheet-sorting assembly comprising a driven supply conveyor extending uninterruptedly from a supply source to a reject depository; a switch conveyor driven at a more rapid rate than said supply conveyor, biased into and for return to a normal position wherein it is upwardly inclined from said supply conveyor, to intercept and divert all sheets as they advance; means to depress said switch conveyor, under control, to permit reject sheets to continue along said supply conveyor to the reject depository; a series of conveyor means driven at a more rapid rate than said switch conveyor, and normally aligned to receive in succession sheets from said switch conveyor, for conveyance past the end of the last such means to a final receiving station; means operable under control to elevate the advanced end of any selected conveyor means out of alignment with the preceding such means, to divert downwardly an oncoming sheet to a receiving station beneath the thus-raised conveyor means; and off-bearing conveyors beneath each such conveyor means, arranged and driven for transverse removal of sheets there received at a rate more rapid than the rate of feed of the conveyor means thereto.

5. A sheet-sorting assembly comprising a driven supply conveyor extending between a supply source and a reject depository; a switch element shiftable under control between an inoperative position and an intercepting and diverting position, with relation to said supply conveyor; a series of conveyor means each shiftable from a position in alignment with other such means and with the switch element, into a diverting position with respect thereto; and means to effect such shifting, under control, of each of the switch element and the several conveyor means, to primarily sort usable sheets from reject sheets by operation of the switch element, and to secondarily

sort the usable sheets into appropriate receiving stations, beneath the several conveyor means, and beyond the last thereof.

6. A sheet-sorting assembly comprising a driven supply conveyor extending between a supply source and a reject depository; a switch element shiftable under control between an inoperative position and an intercepting and diverting position, with relation to said supply conveyor; a series of conveyor means each shiftable from a position in alignment with other such means and with the switch element, into a diverting position with respect thereto; and means to effect such shifting, under control, of each of the switch element and the several conveyor means, to primarily sort usable sheets from reject sheets by operation of the switch element, and to secondarily sort the usable sheets into appropriate receiving stations, beneath the several conveyor means, and beyond the last thereof; the drive means for the successive sheet conveyors being arranged and organized to progressively increase the speed of advance of a sheet through the assembly to the final receiving station, to open progressively wider gaps between successive sheets.

7. A sheet-sorting assembly comprising a driven supply conveyor extending from a supply source to a reject depository; a switch element biased into and for return to a normal diverting position with relation to said supply conveyor; means to shift said switch element, under control, to an inoperative position, to permit reject sheets to continue along said supply conveyor to the reject depository; a series of conveyor means aligned with each other and with the switch element, biased into and for return to a normal receiving and transferring position, to advance along the series sheets received from the switch element; and means operable, under control, to shift any selected conveyor means from such normal position into a diverting position, to divert a selected advancing sheet.
